UNITED STATES PATENT OFFICE

WILLIAM H. DANCE, OF CAMBRIDGE, MASSACHUSETTS

MOLD FOR FORMING GROOVED CONCRETE BLOCKS

Application filed June 26, 1929. Serial No. 373,701.

The chief object of this invention is to provide a mold adapted to form grooved concrete blocks, and composed of members adapted to be conveniently assembled for use, and knocked down or separated to permit the removal of grooved blocks formed therein.

Other objects are to provide a mold adapted to form blocks of different lengths, and end or corner blocks having continuous end faces closing the grooves at one end.

Of the accompanying drawings forming a part of this specification—

Figure 1 is a top plan view of a mold embodying the invention, parts being broken away and shown in section.

Figure 2 is an end view.

Figure 3 shows at one end a section on line 3—3 of Figure 1, the remaining portion of the figure being a fragmentary side view of the mold.

Figure 3a is a section on line 3a—3a of Figure 3.

Figure 4 is a perspective view of one of the groove-forming partitions shown by the preceding figures.

Figure 5 shows the parts of the partition shown by Figure 4, separated from each other.

Figure 6 is a fragmentary perspective view, showing portions of the bottom and side members of the mold.

Figure 7 is a perspective view of the dividing plate shown by Figures 1 and 3.

Figure 8 is a perspective view, showing a portion of a wall formed by blocks made in the mold.

Figure 9 is a section on line 9—9 of Figure 8.

The same reference characters indicate the same parts in all of the figures.

My improved mold comprises a flat-sided bottom member 12, and two movable side members 13, adapted to stand in operative positions relative to the bottom member, as shown by full lines in Figure 6, and to be moved to inoperative positions, as indicated by dotted lines.

The side members are preferably connected with the bottom member by hinges 14, the

arrangement being such that the side members are perpendicular to the bottom member when in their operative positions.

The bottom member 12 is adapted to form the flat side faces 15 and 15a, and the side members 13 are adapted to form the flat end faces 16 and 16a of a concrete block.

The mold comprises also a plurality of removable partitions forming the sides of mold cavities extending across the bottom member 12, between the side members 13, and adapted to form grooved sides in the blocks formed in said cavities, each grooved side including a flat marginal face portion 17, and a recessed face portion 18.

Each partition includes a flat-sided body 19, and groove-forming bosses 20, projecting from opposite sides of the body. I provide means separably connecting the partitions with the side members 13, to maintain the side members in their operative positions and permit the displacement of the side members and the removal of the partitions, said means being preferably embodied as next described.

Each partition body is provided at its opposite ends with extensions forming end tongues 21, removably inserted in spaced apart slots 22 in the side members 13, and with abutment shoulders 23, bearing separably on the inner sides of the side members.

When the side members are in their operative positions, they bear on the abutment shoulders 23, and the tongues 21 project through the slots 22. The tongues are provided with orifices 24, formed to receive separable confiners 25, bearing on the outer sides of the side members 13, said confiners being preferably wedges, as shown by Figure 1.

When the confiners are removed, displacement of the side members 13 from their operative positions and removal of the partitions are permitted.

When fillings of concrete deposited in the mold cavities have sufficiently solidified, they constitute grooved blocks. To permit the removal of the blocks from the mold, the confiners 25 are removed, and the side members 13 are swung outwardly. The partitions and molded blocks may then be removed one at a time, the removal of each partition permitting

the removal of a block. Of course, the removal may progress simultaneously from both ends of the mold.

In the mold shown by Figure 1, some of the partition bosses 20 contact at both ends with the side members 13, so that the mold cavities are adapted to form blocks with recessed face portions 18, extending through the ends of the blocks. Other partition bosses shown by Figure 1, are shorter than the space between the side members 13 and have closed ends 27, offset inwardly from one of the side members. These bosses are adapted to cooperate with said side member and with two partition bodies 19 in forming the end faces 16 on corner or end blocks shown by Figures 8 and 9, said faces closing the ends of the recessed faces or grooves 18.

To decrease the length of a mold cavity and thus adapt it to form the short corner block shown at the right-hand ends of Figures 8 and 9, I provide a dividing plate 28, shown separately by Figure 7. Said plate is provided with recessed edge faces including central portions 29, formed to enter transverse slots 31 (Fig. 4) in two opposed bosses 20, and end portions 30, formed to bear on said bosses.

I prefer to make the partition body 19 in one piece, and the bosses 20 in another piece, as shown by Figures 4 and 5. The body 19 has a continuous end portion and slots 33 extending from the opposite end of the body to the continuous portion. The bosses 20 are opposite sides of a tube having a continuous end portion insertible in the body slots 33, and slots 34, which receive the continuous end portion of the body. The partition thus constructed is of light weight and well adapted to form the grooved sides of the blocks.

While the charges in the mold cavities are soft, wood strips 38, to which laths may be nailed, may be embedded in the top faces 15a of the charges, these faces being those which are struck or formed by moving a straight edge along the upper edges of the side members 13.

I claim:

1. A mold adapted to form rectangular building blocks having grooves in opposite faces, said mold comprising a bottom member, movable side members adapted to stand in operative positions relative to the bottom member, and to be moved to inoperative positions, said bottom and side members being adapted to form flat faces on the blocks, and removable partitions forming the sides of mold cavities between the side members, and adapted to form grooved sides on the blocks formed in said cavities, each partition including a flat-sided body and groove-forming bosses projecting from opposite sides thereof, and means separably connecting the partitions with the side members to maintain the side members in their operative posi-

tions, and permit the displacement of the side members and the removal of the partitions, the body of each partition having a continuous end portion and slots extending from the opposite end of the body to said continuous portion, the bosses being opposite sides of a tube having a continuous end portion insertible in the body slots, and slots which receive the continuous portion of the body.

2. A mold adapted to form rectangular building blocks having grooves in opposite faces, said mold comprising a bottom member, movable side members adapted to stand in operative positions relative to the bottom member, and to be moved to inoperative positions, said bottom and side members being adapted to form flat faces on the blocks, and removable partitions forming the sides of mold cavities between the side members, and adapted to form grooved sides on the blocks formed in said cavities, each partition including a flat-sided body and groove-forming bosses projecting from opposite sides thereof, and means separably connecting the partitions with the side members to maintain the side members in their operative positions, and permit the displacement of the side members and the removal of the partitions, the body of each partition having a continuous end portion and slots extending from the opposite end of the body to said continuous portion, the bosses being opposite sides of a tube having a continuous end portion insertible in the body slots, and slots which receive the continuous portion of the body, the bosses of at least two partitions having transverse slots, the mold comprising also a dividing plate adapted to decrease the length of a mold cavity, and having recessed edge faces whose central portions are formed to enter transverse slots in two opposed bosses, and end portions formed to bear on said bosses.

3. A mold adapted to form rectangular building blocks having grooves in opposite faces, said mold comprising a bottom member, movable side members adapted to stand in operative positions relative to the bottom member, and to be moved to inoperative positions, said bottom and side members being adapted to form flat faces on the blocks, and removable partitions forming the sides of mold cavities between the side members, and adapted to form grooved sides on the blocks formed in said cavities, each partition including a flat-sided body and groove-forming bosses projecting from opposite sides thereof, and means separably connecting the partitions with the side members to maintain the side members in their operative positions, and permit the displacement of the side members and the removal of the partitions, the body of each partition having a continuous end portion and slots extending from the opposite end of the body to said continuous por-

tion, the bosses being opposite sides of a tube having a continuous end portion insertible in the body slots, and slots which receive the continuous portion of the body, the bosses of at least two partitions having closed ends offset inwardly from a side member of the mold to cooperate with said side members and with the bodies of said partitions in forming on a block molded in said cavity, an end face closing the ends of grooves in said block.

In testimony whereof I have affixed my signature.

WILLIAM H. DANCE.
